UNITED STATES PATENT OFFICE.

WILLIAM H. MILLER, OF CRAWFORDSVILLE, INDIANA, ASSIGNOR TO MILLER VEHICLE HEATER COMPANY, OF CRAWFORDSVILLE, INDIANA, A CORPORATION OF INDIANA.

BUTCHER'S VAT.

1,257,726.

Specification of Letters Patent. Patented Feb. 26, 1918.

Application filed November 8, 1916. Serial No. 130,173.

To all whom it may concern:

Be it known that I, WILLIAM H. MILLER, a citizen of the United States, residing at Crawfordsville, in the county of Montgomery and State of Indiana, have invented a new and useful Butcher's Vat, of which the following is a specification, reference being had to the accompanying drawings and to the letters and figures of reference marked thereon.

This invention relates to a unitary structure that is designed to be used for heating water or various substances, more especially in rural districts when hot water is required in which to scald slaughtered animals such as hogs, or when lard or tallow is to be rendered, when soap is to be made or when various other boiling operations are required, the invention having reference more particularly to a structure of the above mentioned character that is designed to be constructed in a factory and shipped complete and which may be readily set up for use by the unskilled wherever required on a farm or elsewhere.

An object of the invention is to provide a new and useful article that shall be so constructed as to be convenient at all times to be used for various purposes incidental to the pursuits of agriculture, or in butchering operations, or when it is desired to heat any substance in considerable quantity. Another object is to provide an improved butcher's vat that may be constructed inexpensively and have a heating furnace permanently connected thereto and which shall be highly efficient, durable and economical in use whether in-doors or in unprotected positions.

With the above-mentioned and other objects in view the invention consists in a vessel and a fire-box of novel construction, and novel means for supporting slaughtered hogs conveniently to the vessel, the invention consisting further in the parts and combinations and arrangements of parts as hereinafter particularly described and further defined in the accompanying claims.

Referring to the drawings,—Figure 1 is a

side elevation of a vat constructed substantially in accordance with the invention. Fig. 2 is a front elevation of the structure of which parts are in folded position. Fig. 3 is a top plan of Fig. 1. Fig. 4 is a fragmentary sectional elevation on the line IV—IV on Fig. 1. Fig. 5 is a section on the line V—V on Fig. 3. Fig. 6 is a section on the line VI—VI on Fig. 1. Fig. 7 is a perspective view of one of the parts of the structure; and, Fig. 8 is a fragmentary section on the line VIII—VIII on Fig. 3.

Similar reference characters on the different figures of the drawings indicate like parts or features of the invention herein referred to in detail.

In practically carrying out the objects of the invention, a metallic fire-box structure is provided which preferably is composed of sheet metal and mainly comprises a front wall 1, a rear wall 2, each wall having a concave top, and side walls 3 and 4 connected to the front and rear walls, the side walls preferably being inclined so as to extend upwardly convergently in order that relatively broad fire grate surface may be conveniently provided. In order that the structure may be conveniently supported upon the surface of the ground which in some cases may not be solid, the front and rear walls preferably are provided respectively with outwardly extending base portions 5 and 6, the side walls being likewise provided with similar base portions 7 and 8 respectively. The inner side of the front wall is provided with a grate support 9, the rear wall being provided with a similar grate support 10, and a cross-bar 11 is secured to the side walls 7 and 8 for supporting the middle portions of grate bars 12 which rest upon the supports 9 and 10. The front wall 5 has a doorway 13 therein through which to insert fuel into the fire-box and is normally closed by a fire-door 14 mounted on the front wall. A draft-pipe is provided which comprises a horizontal section 15 which is connected to the rear wall 2 and to which an elbow 16 is connected, a section or sections 17 being connected to the elbow in

upright arrangement and provided on the top thereof with a suitable hood 18. The top of the fire-box is composed of the bottom portion of a vessel adapted to contain liquid and comprising a main portion 19 which is curved so as to be approximately semi-circular in cross-section, thus being concave interiorly, the lower portion being secured upon and supported by the walls of the fire-box structure. The front end portion 20 of the vessel is connected to the main portion 19 and is sloping, the top thereof being curved. The front end portion of the vessel projects forward beyond the front wall 1 of the fire-box structure. The vessel extends rearward beyond the rear wall 2 and has a vertical rear end 21 to which a brace 22 preferably is connected, the brace being connected to the upright portion of the draft-pipe. The metal at the top of the wall portion of the vessel is turned over a wire 23 to form a bead 24, portions of the wire being conveniently utilized as hinge rods whereby two tables 25 and 26 are connected to the opposite side portions of the vessel, the table 25 having hinge devices 27 and 28 on its normal inner edge that are connected to the wire, the table 26 having similar hinge devices 29 and 30 that are connected to other portions of the wire, the arrangement being such as to permit the tables to hang at the outside of the vessel or be supported in a slightly inclined position so that liquid shall drain therefrom into the vessel, the hinged portions of the tables having water-sheds 31 and 32 respectively that are adapted to extend over the adjacent top portions of the vessel to conduct the liquid from the tables to the interior of the vessel. The forward ends of the tables have laterally projecting portions 33 and 34 respectively that extend partially over the curved top of the inclined front portion 20 of the vessel, space being left however between the tables to permit the passage of a carcass over the front end portion of the vessel.

The tables of the vat are provided with suitable props adapted to support the tables in proper position for use, and for this purpose one side wall of the fire-box structure is provided on its outside with sockets 35 and 36 adjacent to the base portion of the wall, the opposite side wall being provided with similar sockets 37. A suitable number of props 38, 39, 40, 41 are provided, being composed of metal, each prop having a foot portion 42 that is adapted to be inserted into any one of the sockets, and a head portion 43 that is adapted to be connected with a clasp 44 secured to the under side of the table adjacent to the normal outer edge thereof, each table being provided with a suitable number of clasps which are adapted

to permit the head portions of the props to be readily disengaged therefrom.

In practical use, when the vat is required for butchering operations water is heated in the vessel, and after a carcass is scalded in the hot water it is drawn upward on the inclined front end portion 20 and rolled over onto either one of the tables, after which the bristles are scraped from the hide of the animal, and various other operations may be performed on the table, the work being carried out with a saving of time by working on both sides of the vessel. The vessel may be conveniently used at other times in lieu of a kettle in which to evaporate the natural liquids to produce maple syrup or cane syrup, the vessel being useful also for rendering lard and also for drying fruits or other substances.

Having thus described the invention, what is claimed as new is:—

1. In a butcher's vat, the combination of a front wall and a rear wall spaced apart, each wall having a concave top, a vessel having a convex under portion seated upon and secured to the concave tops of said walls, two side walls standing at an inclination and extending upward convergently each to the other, said side walls extending to said convex portion of the vessel and secured thereto, said side walls being connected to said front wall and rear wall, a grate-support arranged at the lower inside portion of said front wall and secured thereto, a grate-support arranged at the lower inside portion of said rear wall and secured thereto, a cross-bar secured to the lower inside portions of said side walls, and a fire-grate upon said grate-supports and said cross-bar.

2. In a butcher's vat, the combination of a front wall, a rear wall, two side walls connected to the front wall and the rear wall, the lower outside portion of each side wall having a plurality of sockets thereon, a trough-like vessel secured to the top of each one of said walls and extending outward beyond the front and rear walls, tables hinged to the top portions respectively of the vessel, clasps secured to the under side of the tables, each clasp being open at one side, and a plurality of props having each a foot portion that is inserted rotatively in any one of said sockets, each prop having a head portion to be laterally swung into any one of the clasps through the open side thereof on rotation of the foot portion in the socket.

3. In a butcher's vat, the combination of a fire-box structure, a fire-grate in the structure, an open-top water-holding vessel having concave bottom and side portions, the forward end portion of the bottom and sides being sloping to constitute a chute and having a curved top, the bottom portion of the vessel being secured upon the top of the fire-

box structure, and two tables hinged at one side to the side portion tops respectively, the tables having forward end portions extending laterally each toward the other and partially over the curved top of the sloping end portion of the vessel, and props connected to the tables respectively.

In testimony whereof, I affix my signature in presence of two witnesses.

WILLIAM H. MILLER.
